(57) **CLAIM**

The ornamental design for a bike hanger, as shown and described.

DESCRIPTION

FIG. 1 is a front, left and bottom perspective view of a bike hanger showing my design;

FIG. 2 is a rear, right and top perspective view of the bike hanger in FIG. 1;

FIG. 3 is a front elevation view of the bike hanger of FIG. 1;

FIG. 4 is a rear elevation view of the bike hanger of FIG. 1; FIG. 5 is a left side elevation view of the bike hanger of FIG. 1;

FIG. 6 is a right side elevation view of the bike hanger of FIG. 1;

FIG. 7 is a top plan elevation view of the bike hanger of FIG. 1;

FIG. 8 is a bottom plan elevation view of the bike hanger of FIG. 1; and,

FIG. 9 is another front, left and bottom perspective view of the bike hanger in FIG. 1 in another state.

The broken lines shown in the drawings are included for the purpose of illustrating portions of the bike hanger that form no part of the claimed design.

1 Claim, 9 Drawing Sheets
